RATION OF MASSACHUSETTS.

CAN-LABELING MACHINE.

1,268,442.

Specification of Letters Patent. Patented June 4, 1918.

Application filed November 5, 1917. Serial No. 200,229.

To all whom it may concern:

Be it known that ARVID P. EKVALL and HERMAN STAKE, both citizens of the United States, residing at Worcester, in the county of Worcester and State of Massachusetts, have invented certain new and useful Improvements in Can-Labeling Machines, of which the following is a specification.

Our present invention relates to a novel construction and organization of mechanism for gumming or applying adhesive substance to the end portion of the labels, the same being adapted for use on that class of can-labeling machines wherein the labels are affixed by rolling the cans over the pack of labels on a label-supply holder.

The prime object of our invention is to provide an efficient, convenient and desirable gum-applying means that can be operated at a high rate of speed. Also, to afford a can-controlled mechanism of the character specified, having means for interrupting the gumming action whenever a can is absent from the regular order of serial advancement.

These objects we attain by mechanism the nature, organization and mode of operation of which is more fully set forth in the following detailed description, with reference to the accompanying drawings, (three sheets) wherein Figure 1 represents a front side elevation. Fig. 2 is a rear elevation; Fig. 3 a vertical transverse section through the oscillating shaft and label box, at line X X on Fig. 1. Fig. 4 is a detail view of the cam which actuates the applier-supporting lever. Fig. 5 is a detail view of the cam and connections for tilting the gum-applier. Fig. 6 represents a top plan view of the mechanism with the gum-applier at position as when in contact with the label. Fig. 7 is a horizontal sectional plan view of the shafts, cams and levers below the gum reservoir, with dot-and-dash lines indicating the position of the label-box and the relative location of the gum-applier when retracted. Fig. 8 is an outline diagram indicating the arrangement of the drive-gear-

ing; and Fig. 9 is a diagrammatic view illustrating the action of the gum-applier. 50

As illustrated this mechanism is more especially adapted to a can-labeling machine of the general character set forth in Letters Patent No. 1,238,710, granted us August 28, 1917; but may be employed upon 55 other labeling machines in similar manner.

In referring to the drawings, numeral 20 denotes the supporting bed or frame, which may be of any suitable construction; B the over head propelling belts, which may be 60 mounted on pulleys B* and operated as heretofore employed; and R indicates the runway along which the cans C roll while being labeled.

Numeral 10 indicates the label-box for 65 containing the supply of labels L, which are supported therein, backs upward, upon a vertically movable plate 11, having an elevating standard 12 with which any well known or suitable elevator mechanism may 70 be combined for keeping the top of the label pack at approximately uniform level with the runway, as labels are taken therefrom.

Any well known or suitable means can be 75 employed for touching the top surface of the pack and for controlling the action of the elevator mechanism, but said elevating and elevator-controlling devices, not being claimed as of our present invention, are 80 not herein shown.

The front side 10* of the label-box is removable to facilitate charging the labels into said box, and can be retained in position by one or more thumb screws I or other 85 equivalent fasteners.

Numeral 13 (Fig. 6) indicates the primary gum-applying roll or device for imprinting adhesive substance upon the surface of the can, as heretofore practised; it being located 90 in such relation that the rotation of the can brings the gummed area down upon the first end of the uppermost label in the label-box, causing said end to adhere to, and be picked up by the rolling can, as will be fully 95 understood.

The term "gum" or "gumming," as employed in this specification, is intended to include as an equivalent, the use of paste, glue, mucilage or any other suitable adhesive substances such as may be employed for sticking labels upon the articles to which they are affixed.

Numerals 15 indicates the tracks along the sides of the label-box, upon which the 10 rims of the cams roll; and 16 indicates parallel side guards or rails defining the runway, and for embracing the ends of the cans to keep them in proper alinement with the labels.

15 The tracks upon which the cans roll are preferably formed with a depression 14 at the front end of the label-box coincident to the pick-up position, to allow the gummed spots upon the can to press more firmly upon 20 the label. The tracks are also preferably slightly arched at 18, where the can passes over the gum-applier devices.

Numeral 17 indicates the gum reservoir supported upon and closely adjacent the end 25 of the label-box, the base of which is extended 10^b, and provided with means for removably attaching said reservoir thereto; so that it and the gum-delivering devices will bear the same relation to the latter end 30 of the pack of labels whether the label-box is adjusted for longer or shorter labels, as required for various sizes of cans. In the present instance the reservoir is removably retained in position by engaging lugs *a*, a 35 notched step *e* and a spring pressed latch device *b*, as illustrated. The gum-devices may be readily released from its position by pressing back said latch.

Numeral 2 indicates the gum-delivery 40 roller disposed in transverse relation to the runway, and rotatable within the reservoir; its journals being mounted in suitable bearings upon the sides of said reservoir. An adjustable scraper-gage 4 is arranged thereon 45 for regulating the amount of gum delivered, which is controlled by a regulating screw 4^a arranged in approved manner. Numeral 3 indicates a transfer-roll arranged parallel with the delivery roll 2 to take gum therefrom; and is supported to turn in bearings 50 preferably attached to the front part of the reservoir. This transfer roll is located outside the end wall of the label-box, adjacent the top corner thereof, and slightly below 55 the top-plane of the pack of labels; said parts being respectively positioned substantially as illustrated. The top of the end wall of the label-box is best made slightly lower than the top plane of the pack of labels. 60 (See Figs. 1 and 9.)

Supported in suitable bearings or brackets 21, attached to the extended base 10^b of the label-box 10, we arrange a rotatable shaft 23, and an oscillative shaft 24; the former be-

ing operated by a sprocket and chain 26, or 65 other suitable means, from the main drive 28, or other moving part of the can-labeling machine. The shaft 24 is provided with an arm 25 having a stud-roller 25^a thereon that engages with a cam 30 fixed on the shaft 23, 70 whereby oscillative or rocking action is imparted to the shaft 24 and parts connected therewith, synchronally. A spring 27 is provided for keeping the roller 25^a against the face of the cam 30 and for moving the 75 arm and connected parts in one direction, while the cam controls their movement and actuates them in the other direction.

Fixed upon the shaft 24 and extending upward past the ends of the gum-reservoir, 80 are two carrier-arms or supporters 31 and 31^a, having between their upper ends a transversely disposed gum-applying element, the bar or plate 32 of which is pivoted or hingedly supported at its ends 33 with the carrier means. The bar 32 is provided with a rigid or integrally attached backwardly projecting member 34 to which the actuating means is pivotally connected. The carrier-arm 31^a is best offset or curved, as shown in 90 Fig. 5, so as to clear the roll-driving gears. Upon the bar 32 there is a forwardly projecting open plate or gum-applier member 5, having a flat under surface corresponding in form and size to the area of that portion of the label which is to be coated with gum or adhesive substance; this being preferably a rectangular strip across the rear end of the label, about one-half inch, more or less, in width. The gum-applier plate 5 and bar 32 100 may be integral and solid; but preferably the plate is provided with a back member 6 that is firmly attached to the bar 32 by screws *x*, or other approved fasteners; the gum-applier-plate and back member being for lightness of structure formed open at the center and integrally united by slightly arched arms 7. The gum-applier projects 105 for some distance forward from the bar sufficiently to reach over the gum rollers, as illustrated, for printing gum upon the labels. 110

Numeral 35 indicates a cam fixed upon the rotating shaft 23; and 36 is an upwardly and downwardly acting lever or arm, having a stud roller 36^a that engages said cam. A suitable spring 37 is provided for effecting movement in opposition to the cam action. The fulcrum hub of said arm is preferably mounted to turn loose upon the oscillating shaft 24. Pivotedly attached to the arm 36 there is a connector or link element 39, the upper end of which is pivotally attached to the arm 34 of the bar 32 for tilting or rocking the gum-applier on its carrier by actuation of the arm 36 by the cam 35. The connector is provided with an intermediate hinging joint 40 adapted to permit backward knuckle-joint flexure, but to resist for 125

ward flexure beyond its straight alinement, it having contact lugs or stop surfaces 41 therefor. A suitably arranged spring 42 is combined therewith for reestablishing its 5 straight alinement when the flexing force is relieved. A laterally projecting pin or lug 45 is arranged in or upon the connector bar 39 below the hinging joint.

At the back of the label-box 10, and projecting up through the track 15 upon which the cam C rolls, there is arranged a movable 10 detent or depressible can-actuated member 46 which is connected with one arm of a lever 47, fulcrumed on a stud 48, and having 15 a rearward arm extending to and terminating adjacently in front of the pin 45 fixed on the connector bar. The detent 46, when free, is normally held at elevated position by a suitably arranged spring 49.

20 The gum-roll 2 and transfer roll 3 are given rotative movement from the shaft 23 by a train of gearing preferably arranged as indicated by the diagram Fig. 8; and comprising a sprocket 51 fixed on shaft 23, 25 a chain 52 connecting therefrom to a sprocket 53 and spur gear 54 mounted on a stud fixed on the frame; an intermediate stud-supported gear 55 meshing with said spur gear; a gear 56 fixed on the axle of the gum-roll 30 2 and engaging with said intermediate gear; and a gear 57 upon the axle of the transfer-roll 3, meshing with the gear on the gum-roll axle, the movement of the several gears being in the direction severally indicated by 35 the arrows.

The cans are fed into the runway R and rolled forward by the belts so that in normal action they follow each other at regular spaced intervals; the rate of their approach 40 being timed to correspond with the cycle of action of the described gumming apparatus. The spacing may be accomplished by suitable feed-spacing mechanism; which being a separate invention is not herein described. It frequently occurs, however, that 45 for one reason or another one or more cans may be omitted from the regular spaced serial order while the machine is running. Such condition is provided for in the action 50 of our improved mechanism as explained.

The operation is as follows: Assuming that the machine is running and that the parts are at the positions indicated in Fig. 1, and by full lines in Fig. 9; the can C 55 having been primarily gummed and having picked up the first end of the label, as the can C approaches the rear end of the label-box the cam 30 upon the rotating shaft 23 actuates the lever arm 25, oscillating the shaft 24 and causing the arms 31 and 31^a to swing forward, carrying the bar 32 and gum-applier 5, the face of which has been previously charged with gum or adhesive, toward the end of the pack of labels L, to

the position shown in Fig. 6. At about 65 the same time the cam 35 actuating the lifter arm 36, raises the connector 39, which is pivoted to the backwardly projecting arm 34 of the rocking-bar 32 upon which the gum-applier 5 is mounted; thus moving or 70 tilting the gummer face toward the label. This movement is effected approximately at the same time or just subsequent to the can C having rolled onto and depressed the detent 46 and thereby lifting the lever arm 47; 75 thus permitting the pin or lug 45 to pass under said lever, as indicated at 45^b, Fig. 9, so that the connector 39 remains straight and elevates the rear end of the arm 34 to the level position, or tilting the gum-applier 80 to bring its gum-charged face down upon the label-pack (see position 5^b Fig. 9) imprinting a film of gum across the lap-end of the topmost label, just before the can C rolls over the same, and pulls the label from 85 the retreating gum-applier. Further rotation of the shaft and controlling cam permits the spring 37 to return the parts to their former positions.

As the gum-applier moves rearward its 90 face is drawn in contact with the transfer roll 3 which puts a new charge of gum upon said gum-applier ready for the succeeding action.

If, in the running of the machine, a can 95 is omitted from the regular serial order, then the detent 46 and lever 47 will of course not be actuated. In that event, when the carrier arms and gum-applier move forward, the pin or lug 45 on the jointed connector 39 engages the end of the lever 47 and carries it upward to the position 45^c, Fig. 9. This causes the knuckle-joint 40 to be forced backward, (see dot-and-dash lines, Fig. 9) thereby diverting or shortening 100 the effective length of the connection between the arm 34 and lever 36, so that the gum-applier 5 when moved forward over the end of the label-box will be tilted up to a position (5^c Fig. 9) where its face cannot 110 come in contact with the label; thus avoiding the spreading of gum upon a label when it cannot be immediately picked up by an advancing can. As the gum-applier is retracted and the parts swing backward the 115 knuckle-joint 40 is straightened by the force of the spring 42 and the parts all return to their normal relation preparatory to the succeeding operation.

When adjusting this mechanism to accommodate different sizes of cans the only change required in the gumming means is to remove the screws α and replace the applier plate 5-6 by a corresponding plate of the desired width; a comparatively simple and inexpensive matter; the bar portion 32 of the applier, which forms its pivotal fulcrum upon the reciprocating moving car-

rier members; the gum-supply devices and rolls 2 and 3 require no change in relation to their support upon the label-box section, since adjustment of the latter upon the bed 5 carries all such parts with it.

What we claim as of our invention and desire to secure by Letters Patent, is—

1. In a can-labeling machine of the class specified, in combination with the label-supply box, means for directing and feeding cans or the like along the opening to said label-supply, gum-supply devices, including a gum reservoir, a gum-delivering roll therein, and a transfer-roll adjacent to 10 the end wall of the label-box; a gum-applier plate adapted for contact with said transfer-roll and for impressing gum upon the end portion of the topmost label within said label-box, including a transversely disposed horizontally pivoted support-bar having a forwardly projecting gum-applier member thereon, means for imparting forward and backward movement to said support-bar and gum-applier member, and 15 means for effecting a tilting action thereof on its pivotal axis.

2. In a labeling machine, the combination of a runway for cans or the like, a label-supply delivering to said runway; means for 20 advancing the cans along the same, a gum-applier plate disposed for gumming lap-ends of labels having reciprocal movement in endwise relation to the labels, carrier means whereon said gum-applier plate is 25 pivotally supported, means for actuating said carrier, means for tilting said gum-applier plate in relation to its carrier, a gum-supply reservoir, a gum-delivering roller rotatable in said reservoir, a coacting transfer-roll adjacent the end of the label-supply and path of said gum-applier, and means 30 for effecting and controlling reciprocatory and pivotal movements to bring the face of said gum-applier plate alternately into 35 contact with said transfer roll and the label.

3. In a can-labeling machine, comprising a runaway for rolling cans, a primary gumming means, a label box for containing a pack of labels with the topmost label approximately in the plane of the runway, and means for rolling the cans along said runway and labels, a final end-gumming means coöperating therewith and including a gum-supply, a stationarily journaled gum transfer-roll adjacent to the end wall of the label-box, and a tiltable gum-applier member, pivotal mountings therefor, and forwardly and backwardly swinging arms adapted to alternately carry said gum-applier into contact with said transfer-roll and the label.

4. In a label-gumming mechanism for the purpose set forth, a gum reservoir supported in connection with the label holder, 65 a gum-delivering roll mounted thereon, a

transfer roll adjacent to the upper rear corner of said label-holder and receiving gum from the delivery roll, a gum-applier element, supporting means therefor adapted to have forward and backward movement for 70 carrying said applier alternately over the ends of the label-box and against the transfer-roll, means for tilting said gum-applier, means for controlling the tilting action, and means for reciprocally operating the applier-supporting members.

5. In a labeling machine, the combination of a runway, belts for the propelling cans or the like along the runway, an open-top label-holder for supporting a pack of 80 labels accessible to said runway, a primary can-gumming device; means for gumming the lap-ends of the labels, including a gum-applier plate having a defined gum-contact surface, said gum-applier mounted to have 85 a compound swinging action composed of an approximately horizontal oscillation and a vertical tilting motion, means for supporting said gum-applier, and means for effecting independent simultaneous operating control of the vertical tilt motion and oscillative motion imparted thereto, a gum-supply means including a gum-transfer roll disposed adjacent to the label-holder at position for contact of said gum-applier face 95 therewith.

6. In a can-labeling machine, in combination substantially as set forth, a label-supply holder, lap-end gumming devices comprising a reciprocally movable gum-applier 100 plate supported to have tilting action, supporting means therefor adapted for moving said gum-applier to and from the end of the label-supply holder longitudinally thereof, means for tilting said gum-applier 105 for contact with the label when at its forward position, a gum-transfer member against which the face of said gum-applier plate passes when retracted, means for varying the limit of the tilt movement, and means actuated by the label-receiving cam for relieving said tilt-varying means from effective action.

7. In a can-labeling machine, including a runway for rolling cans, a label-supply holder for supporting a pack of labels over which the cans roll, can-propelling belts, a gum-applier means comprising a forwardly projected gum-printing plate united to a transverse horizontally pivoted member adjacently beneath the runway and adapted for tilting action, backward and forward moving carrier members for said gum-applier mounted to have movement in longitudinal relation to the runway, means for operating said carrier members, means for effecting tilting action of the gum-applier including a flexibly attached swinging connector provided with a one-way yieldable joint, and means for resetting said joint, a 115 120 125 130

projecting stud on the side of said connector, a lifter member whereon said connector is fulcrumed, an operating shaft and cam for actuating said lifter, a guard-device engageable with said stud to interrupt the normal movement of said connector, a retracting spring therefor, and a connected detent disposed to be operated by the cam for moving said guard-device away from its engaging position.

8. In a can-labeling machine, a runway for rolling cans, means for supplying label approximately in the plane of the runway, a gum-applying element comprising a transversely disposed pivotally supported bar having a projecting front member thereon forming a gum-printing plate surface in size and form corresponding with the area of gum required on the label, a gum-supplying means including a rotatable transfer-roll located below said gum-printing plate adjacent the label-supply holder, an oscillating carrier supporting said gum-applier element, means for rocking said element upon its carrier, including a knuckle-jointed connector, actuating devices therefor, a resisting member for flexing said jointed connector, and means for automatically rendering said resisting member non-effective by contact of the approaching can while receiving a label.

9. In a can-labeling machine, a gum-applier comprising a transverse pivoting member having an outstanding arm and a forwardly projecting transverse gum-carrying portion, and a back portion united thereto by intermediate extending arms, said back portion being attached to the pivoting member, means for supporting said gum-applier, means for imparting backward and forward motion thereto, a swinging connector attached to said outstanding arm and having an intermediate backwardly flexing automatically self-straightening joint and an engaging stud, means for raising and depressing said connector, an abutting lever normally disposed for intercepting the forward swing of said stud and connector, a spring for returning the lever to normal position, and an actuating member connected with said lever and projecting into the path of the cans, whereby presence of the cans shifts said lever from intercepting position.

10. In a can labeling machine, in combination with a label-supply means, and can-feeding mechanism for advancing cans to receive labels from said supply, a gum-applier comprising a transverse horizontal pivoted bar having a forwardly projecting member comprising a transverse gum-carrying portion and a back portion united thereto by narrow slightly elevated extended arms, said back portion detachably secured upon the pivoted bar, means for supporting said gum-applier, and means for imparting reciprocal and rocking action thereto.

11. In a can-labeling machine, the combination with means for supporting a pack of labels, and means for rolling cans or similar containers over the same; of a tilting gum-applier device having a defined gum-printing plate surface, projectable over the end of the label pack, an oscillating shaft provided with carrier arms whereon said gum-applier is pivotally supported, an endwise movable swinging connector pivotally attached to an arm of said gum-applier device, a lifter pivoted to said connector for imparting endwise movement thereto, a rotating shaft provided with cams for respectively actuating said oscillating shaft and said lifter, a gum-supply means including a transfer roll with which said gum-printing surface contacts when in retracted relation, and means for operating said rotating shaft synchronous with the uniformly spaced feeding of cans through the machine.

12. The combination with the can-supporting tracks, label-box, and gum-supply reservoir, of a rotating shaft and a rocking shaft journaled in brackets mounted upon an extension member on the label-box, upwardly extending carrier-arms fixed on said rocking shaft, a transverse rockable applier-bar pivotally supported on the upper ends of said carrier-arms and having a backward offset member, a forwardly projecting gum-applier face member detachably mounted upon the applier-bar, and its forward portion presenting an under gum-applying contact face, an arm fulcrumed upon said oscillator shaft, means connecting said arm with the offset member of said rockable applier-bar, a pair of cams on the rotating shaft for controlling the gum-applier action, springs acting in opposition to said cams, and means for automatically varying the extent of rocking movement imparted to said applier-bar.

13. In a can-labeling machine, the combination with a supporting bed, a can-guiding way above said bed, means for traveling cans along said way, a primary can-gumming means, a label holder for the supply pack of labels, provided with an extended base seated longitudinally adjustable upon said bed, a vibratively movable gum-applier plate, means including upwardly extending arms upon which said gum-applier plate is mounted for moving to and from the end of the label pack and actuating means therefor carried upon the label-holder extension, means for elevating and depressing the gum-applier in relation to the plane of the labels; of a removably connected gum-supply reservoir supported upon the extended base of the label-holder, the gum-delivering roll journaled upon and partially submerged in said reservoir, a gum-transfer roller disposed adjacent to and parallel with the end of the label-pack and gum-applier face, and with its gum-transferring face

having rolling contact with said gum-distributing roll.

14. In a can-labeling machine comprising a runway for cans, can propelling belts, a label-box for supporting a pack of labels with the top of the pack approximately at the level of the runway, a backwardly and forwardly movable tiltable gum-applier, means for operating said gum-applier; and
15. gum-supply means including a gum-transfer roll adjacent the end of the label-box and below said gum-applier, the top of the rear end wall of said label-box being lower than the normal top level of the pack of labels.
16. In a can labeling machine including a runway for rolling cans, an open label-holder, overlying can-propelling belts, and primary can-gumming means; a lap-end gumming appliance comprising a pivoted lever-element carrying a gum-applying member adjacently below the runway, a pivot-supporter for said lever-element movable toward and from the label-holder,
17. means for reciprocally moving said pivot-supporter and lever-element, means for imparting elevating and depressing action to said lever-element including a variable connection and mechanism for reciprocatively operating said connection, means adapted for actuation by the passing can for controlling the varied effective action of said connection, and means for charging gum upon the face of the gum-applying member.
18. 16. In a labeling machine for cans, the combination, with a label-supply holder having an extension at its end; of a gum-supply reservoir removably mounted upon the extended portion of said label-holder, a gum-delivering roll partially submerged in said reservoir, a gum-transfer roll coating therewith, positioned adjacent the end of the label-holder, a transverse pivotally supported gum-applier plate projecting over
19. said transfer roll, backwardly and forwardly swinging carrier-arms for said gum-applier, bearings firmly attached to the label-holder extension, an oscillating shaft having said carrier-arms fixed thereon, and
20. an operating-shaft mounted in said bearings adjacent thereto; means for actuating said oscillating shaft and means for contacting the gum-applier label actuated from said operating-shaft, and means for imparting motion to said operating-shaft.
17. In a can-labeling machine, comprising a runway for cans, a main supporting bed, primary can-gumming means, and propelling belts; the combination as described
21. of a sectioned label-supply box longitudinally adjustable for longer or shorter labels, its rear end-section provided with a backward extension, a reciprocally moving tiltable gum-applier, carrier devices therefor, carrier actuating means, a gum-supply res-

ervoir, a distributing roll and gum transfer-roll adjacent the end of the label-box, means for tilting and controlling the tilt action of the gum-applier, and a rotating shaft with means for actuating the parts; 70 said gum-supply, gum-applier, carrying and actuating devices and operating shaft being collectively mounted upon the rear end section of the label-box for unitary adjustment therewith.

18. In a can-labeling machine, the combination with a label-box, a can-guiding way along the top of said label-box, means for rolling the cans along said way, a reciprocally moving gum-applier plate, a pair of 80 up-standing arms having said gum-applier tiltably supported between their top ends, their lower ends mounted upon a rocking fulcrum shaft journaled in bearings connected with the label-box, gum-applier actuating means including connections for tilting the gum-applier plate, controlling cams for actuating said parts, an operating shaft therefor, a gum-supply reservoir supported in connection with the end of said 90 label box, a gum-distributing-roll journaled in bearings upon said reservoir, a gum-transfer roll disposed adjacent thereto between said distributing-roll and the upper corner of the label-box, intermeshing spur 95 gears fixed on the axles of the distributing and transfer rolls, and suitable gearing for actuating said rolls from said operating shaft, substantially as set forth.

19. In a can labeling machine, a runway 10 for rolling cans, a label-holder for supporting a pack of labels, overlying can-propelling belts, primary can-gumming means; a lap-gumming appliance comprising a forwardly projecting applier having a gum-carrying face adapted for printing adhesive substance upon the lap-end of the label, carriers at either side of the label-holder upon which said gum-applier is pivotally mounted, operating means for backwardly and forwardly moving said carriers, means for raising and depressing the gum-applying member, means for changing the relation, up and down, of the line in which the face of the gum-applier travels for contacting and non-contacting effect of the gum-carrying face in respect to the top-surface plane of the label-pack, a can-actuated means for controlling the line-changing mechanism, and means for charging gum upon the applier face.

20. In a labeling machine, a runway for cans or the like, can-propelling means, a label holder having an end extension, a lap-end gumming mechanism including an upwardly and downwardly vibrating gum-applier plate having a gum-carrying face adapted for stamping adhesive across the end portion of the label, swinging arms supporting said gum-applier for backward and 11

forward movement in endwise relation to the label-holder, a rocker shaft carrying said arms, and actuating mechanism therefor, mounted in brackets supported upon the label-holder extension, a gum-supply reservoir with gum-delivering and transferring rolls disposed upon the end label-holder between said swinging arms, said gum-supply reservoir and rolls being together removable from the label-holder independently 10 of the gum-applier and its actuating mechanism.

Witness our hands this third day of November, 1917.

ARVID P. EKVALL.
HERMAN STAKE.
